UNITED STATES PATENT OFFICE.

KARL TESSKY, OF CHARLOTTENBURG, GERMANY.

AUTOMATIC LATHE.

1,158,745.

Specification of Letters Patent.

Patented Nov. 2, 1915.

Application filed May 12, 1914. Serial No. 838,024.

To all whom it may concern:

Be it known that I, KARL TESSKY, a subject of the King of Prussia, residing at Charlottenburg, Damkelmannstrasse 33, 5 Germany, have invented certain new and useful Improvements in Automatic Lathes; and I do hereby declare the following to be a full, clear, and exact description of the invention, such as will enable others skilled 10 in the art to which it appertains to make and use the same.

The object of the present invention is an automatic lathe for manufacturing articles in great quantities such as screws, etc. The 15 machine may be called an automatic screw machine of simple and compact design, permitting a considerable increase of the working speed through the accelerating of the successive operations of the working tools. 20 Incidentally the design will considerably facilitate the exchange of certain machine parts such as cam plates in order to arrange the machine for different work. Further the design permits the introduction of an 25 effective safety device against breakage of any machine part or damage to the work in case of sudden disorders or complications during the working process.

In the drawings, Figure 1 is a longitudinal section through the driving spindle of a lathe constructed according to this invention, with some parts omitted. Fig. 2 shows the front view of same. Fig. 3 shows a cross section along A—B of Fig. 1. Fig. 4 shows 35 a vertical longitudinal section along C—D of Fig. 3. Fig. 5 is a cross section along E—F of Fig. 1. Fig. 6 a section along G—J—H of Fig. 3. Fig. 7 shows part of section of Fig. 4 with same details given in 40 outside view. Figs. 8, 9, 10 are views of the gear segments used for transmitting the motion. Figs. 11—12 give front view and top view of one of the cam levers.

1 represents the headstock of the machine 45 supporting the hollow spindle 2, through the bore of which the stock rod is admitted from which the work piece is made. The well known device for gripping and feeding the material is not shown. There are for 50 instance 3 shafts 4, 5, 6 located around the spindle of the headstock, which are supported parallel to the spindle, and to the ends of which, projecting beyond the headstock, are secured rocking levers 7, 8, 9, 55 carrying the tools 10, 11, 12. The number of the shafts depends on the number of the

necessary tools, and, therefore, is controlled by the work to be performed. For example, lever 9 is a conveyer which grips the finished formed work pieces and carries them to the 60 spot where additional machining is to be performed, as for instance, the slotting of the head of screws. The rocking levers or tool holders move, while working, in the direction of the arrows I, II, III. The rocking motion of the tool holders 7, 8, 9 is caused by the cam plates 15, 16, 17, arranged on shaft 14 by means of the following devices.

The forked levers 18, 19, 20 are loose on 70 shaft 6 of lever 9 causing the rolls 21, 22, 23 held in the levers, to press on the circumference of their respective cam plates. The hub of each of the levers 18, 19, 20 carries a geared segment 24, meshing with one of 75 the loose gears 25, 26, 27. The latter are arranged on the stationary tube 3, passing through the headstock and surrounding spindle 2. This causes the cam plate 15 to operate gear 25; cam plate 16 to operate 80 gear 26; cam plate 17 to operate gear 27. Keyed to the shafts 4, 5, 6 are further geared segments located, shaft 4 carrying segment 28, shaft 5 the segment 29, shaft 6 the segment 30. Segment 28 engages with gear 85 wheel 25 and segment 29 with gear wheel 26. However, segment 30 engages with gear wheel 31, the hub of which is firmly connected with the hub of gear wheel 27 in such a manner that both can only perform the 90 same motion. Gear wheels 25, 26, 27 and 31 do not constitute a complete gear, since they do not make a full revolution but only perform rocking motions. Consequently, 95 they are only equipped with segments sufficient for their motions. Their shapes are shown in Figs. 8 to 10 and they appear as rings arranged on tube 3, carrying toothed segments.

While the movements of levers 18 and 19 100 and their respective tool holders 7 and 8 cause neither increase or decrease of speed or of the extent of their travel, this is the case with lever 20 and its respective tool holder 9, as the latter carries a conveyer 12 105 which has the duty to perform to carry the cut off work piece from the spindle to the spot where its further machining takes place, in this case to the slotting saw 13 or for some other purpose, requiring a 110 comparatively large distance to travel. For this reason toothed segments 27 and 31

and in the same way toothed segments 24 and 30 are different in diameter in such a way that the transmission of motion by means of lever 20 on shaft 6 causes an enlargement of the motion.

The drive of shaft 14, carrying the cam plates, can be selected in any suitable way, for instance by means of belts, etc. In this case, the motion is obtained from spindle 10 2 by means of a cross shaft 32 which too is supported in the headstock 1, and carries a worm wheel 33 and a worm 34, the former engaging with a worm 35 on spindle 2, while the latter meshes with a worm wheel 15 36 on shaft 14. Of course, cam plates 15, 16, 17 must be shaped to suit the work to be made, and it is therefore necessary to exchange them for others when different work pieces are to be produced. In most cases, 20 this is time wasting and incidentally inconvenient work, as ordinarily the cam plates are arranged partly within the machine, for which reason they are difficult of access. In order to overcome this objectionable feature, in some cases two parted cam plates are used, or in case it is preferred to use solid cam plates, it is necessary to provide 25 separate shafts which are operated singly from an auxiliary shaft etc. by means of 30 gears and carry on their free ends the solid cam plates.

In order to be able to perform the exchange of the cam plates rapidly and conveniently, the following arrangement has 35 been selected. Shaft 14, carrying worm wheel 36, has been designed as a hollow shaft, and in the preferred form of the machine, as shown in Figs. 4 and 5, one section 38 of this hollow shaft is removable. 40 The shaft 14 therefore consists of three parts or shaft sections 14, 40 and 38. The left hand part 14 is the main part. The right hand part 40 is journaled in a stationary bearing 41 and has a hollow or tubular portion 42. The removable shaft section 38 is tubular and is arranged between the parts 14 and 42. In Figs. 2 and 3 the main shaft 14 is shown as a solid shaft, and is not formed in sections. The cam plates 50 15, 16, and 17, are carried by the removable shaft section 38. The said right hand part 14, or main portion of shaft is supported in the machine frame 43, shaped in box form, and can be utilized for carrying other 55 cam plates for instance 44, 45. The connection between shaft part 14, shaft part 38, and shaft extension 40 is obtained by means of center bolt 46, passing right through the bore of shaft parts 14 and 38, and entering 60 with its front end into the shaft partly designed as hollow shaft. A long feather key 47 keys all the parts, located on center bolt 46, firmly with each other. In case it is required to loosen the connection, the center 65 bolt is moved along its axis by means of its

knurled head 48; in other words, it is pulled out so far from the shafts, in which it fits, so that shaft part 38 is released and can be removed sidewise in the direction of arrow IV, including all the cam plates located on 70 it. After the cam plates have been exchanged, either the same shaft part, or another one which has been held ready, fitted with different cam plates, can be immediately put in place again. The connection is 75 made by pushing center bolt 48 back, and thus coupling shaft part 14 and 40.

As the machine operates with high speed, there is a danger that breakage or damage of the machine or the work will happen, in 80 case the resistance of the work surpasses a certain amount. For example, in case the tool should break, the resulting disturbance would require to stop the machine instantly, in order to prevent damage to the 85 machine. For this purpose, a device has been provided, consisting of the connection of two couplings. As soon as a certain resistance has been reached, one of the 90 couplings will disengage and cause a second coupling, which transmits the drive to disengage momentarily. Trouble of this kind can, for instance, happen on account of 95 conveyer 9, 12, gripping the formed piece, and in moving colliding with the other tools.

Cam plate 17, operating the conveyer arm 9, is connected with sleeve 37 through pins. This sleeve is not keyed to hollow shaft 38, but loose on it. Sleeve 37 is engaged 100 through a beveled tooth clutch, of which one half 39 is firmly connected with sleeve 37, while the other half 77 is arranged so that it cannot turn on hollow shaft 38, by means of feather and key, but can be shifted sideways. Spring 78, which can be regulated by 105 means of nut 79, insures proper engagement of sleeve 77.

Stationary stop 68 is located on the machine bed, and keeps the angular lever 66 in position, causing the free end 82 of the other lever arm 80 to be secured a little distance from the edge 81 of the sliding half 77 of the coupling. The end 65 of lever arm 66 touches the end 64 of a trigger-lever 63, of which the nose 61 rests against the nose 60 of the double armed lever 59, supported at point 57 of the machine bed. This causes the upper end 56 to hold coupling sleeve 55 in engagement with the driving pulley 52, opposing spring 58.

In case the conveyer should interfere, or a similar incident occur, resulting in a disturbance of the working process, and thus the normal resistance be considerably increased, this would prevent cam plate 17 115 from turning and push the sliding coupling half 77 in the direction of arrow V. Further, by means of edge 81 the lever 77, 66 and incidentally lever 63 are moved, nose 60 of lever 69 is released, and the effect of 120

spring 58 causes coupling sleeve 55 to move, which momentarily stops the drive of the machine, thus preventing any damage of machinery parts or of the work. It is evident 5 that not only cam plate 17, but also each of the others can be connected with this device and thus safe guarding the parts depending on it. In the same way, it is possible to disconnect any shaft, for instance 10 the working spindle, in case of overload. In this case, the driving pulley 52 bears not directly on the spindle but is placed correspondingly loose on a sleeve 53, which, in turn, itself is loose on spindle 2. However, 15 it cannot slide on sleeve 53, and is coupled with it by means of clutch coupling 54, of which sleeve 55 is operated in the described manner by means of lever 56.

Lever 69 has its fulcrum on shaft 62, 120 which supports lever 63, having a nose 61. End of lever 69 touches with its end 70 the front-face 71 of the sleeve 72, which is the coupling with beveled teeth which cannot turn on the spindle but slides on it. The 125 other half 73 of this beveled tooth coupling is firmly connected with sleeve 53. Sliding sleeve 72 is kept in engagement continuously with coupling half 73 by means of spring 74, the pressure of which can be regulated through nuts 75. Only in case of sudden increase of the working resistance at the 130 spindle, the pressure of the beveled teeth 76 will cause the coupling to slide apart, and in consequence sleeve 72 will be pushed away from sleeve 73. This causes a movement of 135 lever 69, together with lever 63, with the result that nose 61 is lifted and the machine disengaged momentarily, in the same manner as described before. In the same way, 140 it would be possible to arrange the clutch coupling, or, if desirable simultaneously the beveled teeth clutch on the cross shaft 32 so that the couplings can be located on any 145 shaft of the machine selected. It is of importance to place the clutch coupling on the driving part of the shaft, while the beveled tooth clutch should be located on the driven shaft which is to safeguard 150 against overload through sudden disengagement. The parts to be connected with each other in a corresponding manner.

What I claim is:—

1. In a lathe, the combination, with a 155 lathe spindle, of a series of rock-shafts arranged around the lathe spindle and provided with lever arms for supporting tools, toothed segments secured on the said rock-shafts, a revoluble cam shaft, cams secured on the said cam shaft, pivoted cam levers operated by the said cams and provided with toothed segments, and toothed gears mounted concentric with the lathe 160 spindle and operatively connecting the toothed segments of the cam levers with the toothed segments of the rock-shafts.

2. In a lathe, the combination, with a lathe spindle, of a series of rock-shafts arranged around the lathe spindle and provided with lever arms for supporting tools, toothed segments secured on the said rock-shafts, a revoluble cam shaft, cams secured on the said cam shaft, pivoted cam levers operated by the said cams and provided with toothed segments, a stationary sleeve encircling the said lathe spindle, and toothed 170 gears mounted to oscillate on the said sleeve and operatively connecting the toothed segments of the cam levers with the toothed segments of the rock-shafts. 75

3. In a lathe, the combination, with a lathe spindle, of a series of rock-shafts arranged around the lathe spindle and provided with lever arms for supporting tools, toothed segments secured on the said rock-shafts, a revoluble cam shaft formed of 180 three shaft sections arranged end to end, stationary bearings for the two end sections to revolve in, a disengageable coupling device connecting the middle shaft section with the end sections and permitting its removal from between them, cams secured on the middle shaft section, pivoted cam levers operated by the said cams and provided with toothed segments, and toothed gears mounted concentric with the lathe 190 spindle and operatively connecting the toothed segments of the cam levers with the toothed segments of the rock-shafts. 195

4. In a lathe, the combination, with a lathe spindle, of a rock-shaft arranged parallel to the lathe spindle and provided with a lever arm for supporting a tool, a revoluble shaft also arranged parallel to the lathe spindle, driving mechanism for operatively connecting the revoluble shaft with the rock-shaft, a driving pulley, a clutch which normally connects the driving pulley with the lathe spindle, a spring-operated trigger-lever for disengaging the members of the said clutch so as to stop the machine, an automatic clutch normally connecting the said driving mechanism with the rock-shaft and disengaging automatically when the resistance to the movement of the rock-shaft exceeds a prearranged limit, and lever mechanism operatively connected with the slidible member of the automatic clutch and provided with a catch which normally engages with the said trigger-lever and thereby holds the members of the first said clutch in driving engagement with each other. 110 115

5. In a lathe, the combination, with a lathe spindle, of a sleeve mounted loosely on the lathe spindle, a driving pulley mounted loosely on the said sleeve, a clutch which 120 normally connects the driving pulley with the said sleeve, a spring-operated trigger-lever for disengaging the members of the said clutch so as to stop the machine, an automatic clutch normally connecting the said 125 130

sleeve with the lathe spindle and disengaging automatically when the resistance to the motion of the lathe spindle exceeds a prearranged limit, and lever mechanism operatively connected with the slideable member of the automatic clutch and provided with a catch which engages with the said trigger-lever and normally holds the members of the

first said clutch in driving engagement with each other.

In testimony whereof I affix my signature, in presence of two witnesses.

KARL TESSKY.
